UNITED STATES PATENT OFFICE.

WILLIAM E. HUGHES, OF SEATTLE, WASHINGTON.

DOOR-LOCK ELECTRIC SWITCH.

No. 853,791.

Specification of Letters Patent.

Patented May 14, 1907.

Application filed July 17, 1906. Serial No. 326,576.

To all whom it may concern:

Be it known that I, WILLIAM E. HUGHES, a citizen of the United States, residing at Seattle, in the county of King and State of Washington, have invented certain new and useful Improvements in Door-Lock Electric Switches; and I do hereby declare the following to be a full, clear, and exact description of the invention, such as will enable others skilled in the art to which it appertains to make and use the same.

This invention relates to electric switches, and especially to switches designed for association with door locks, and so arranged that locking the door will open the switch and break the circuit.

A further object of the invention is to provide an electric switch mounted upon a frame, and adapted to be inserted into the mortise of a door frame, and provided with a switch operating lever positioned to engage the end of the locking bolt of the door lock when thrown.

It is well known that especially in hotels using electric lights to light the various apartments and bedrooms that guests will leave their rooms and lock their doors, and remain absent for a considerable length of time, without extinguishing the lights, and whereby the expense of operating the said lights is continued when such lights are not in use.

The present invention is designed to economize electric current by extinguishing the lights of the apartment whenever a door is locked from the outside, so that as soon as the guest leaves the room and locks the door the use of the current is discontinued for that room, but the lights instantaneously relighted when the door is unlocked for the tenant to enter the room.

With these and other objects in view, the invention comprises certain other novel constructions, combinations and arrangements of parts, as will be hereinafter fully described and claimed.

In the drawings:—Figure 1 is a view in side elevation of the improved switch associated with the conventional door lock, with the switch open to break the circuit. Fig. 2 is an end view of the switch with the strike plate removed and taken on line 2—2 of Fig. 1. Fig. 3 is a view of the improved switch closed partly in side elevation and with certain parts broken away, as taken on line 3—3

of Fig. 2. Fig. 4 is a top plan view of the switch showing the top end of the switch operating lever broken away and taken on line 4—4 of Fig. 3.

Like characters of reference designate corresponding parts throughout the several views.

In its preferred embodiment, the invention forming the subject-matter of this application, comprises upper and lower frame pieces 10 and 11, respectively rigidly secured at one end to a strike plate 12 of substantially the usual and ordinary construction, which tie the said frame pieces together. The frame pieces 10 and 11 are further tied together and strengthened by cross bars 13 and 14 disposed at a little distance from the strike plate. The strike plate 12 is provided with the usual latch receiving opening 15, and bolt receiving opening 16 adapted respectively to receive latch 17 and bolt 18 of the lock shown conventionally at 19.

Between the crosspieces 13 and 14 the switch operating lever 20 is journaled by means of a transverse shaft 21 and is engaged at its upper end by a spring 22 and at its lower end is provided with a downwardly extending arm 23 preferably provided at its extremity with a cross head 24 extending over the bolt receiving opening 16.

Pivoted upon the shaft 21 are the switch arms 25 joined by means of a pin 26 disposed within the notch 27 formed in the lever 20. A spring 28 also surrounds the shaft 21 and is engaged at one end by the lever 20 and at its opposite end engages the pin 26. Upon the lower frame piece 11 are mounted spaced contacts 29 and 30 insulated from the frame piece 11 in any approved manner as by the insulation 31 and respectively connected with wires 32 and 33 in series with the lights of the apartment to be controlled thereby.

The lock herewith shown is provided with a bolt 18, and an auxiliary bolt 34 whereby both the main bolt and the auxiliary bolt may be thrown from the outside of the door and the switch operated thereby while only the main bolt and not the auxiliary bolt will be thrown from the inside of the door and whereby the door may be locked from the inside without extinguishing the lights. The specific structure of the lock here shown is not claimed herein as it forms no part of this invention.

As shown in Fig. 3 the switch and arms 25

are between the contacts 29 and 30 and complete the circuit of the wires 32 and 33 in series with the lights of the apartment as mentioned. In Fig. 3 the main bolt 18 only is shown as shot, but it will be understood that when the device is used with a lock having a bolt of ordinary construction, the bolt cannot be shot without operating the switch. When the bolt 18 is thrown the cross head 24 is engaged by the bolt and the operating lever moved in the direction indicated by the arrow. The contacts 29 and 30 being of resilient structure engage the switch arms with some force and such arms are held from movement until the lower edge of the notch 27 contacts with the pin 26 when the switch plates are disengaged from the contacts 29 and 30, and under the tension of the spring 28 are thrown suddenly out of engagement 20 therein to prevent undue sparking of the contacts at the switch so that the switch assumes the position in Fig. 1. The throwing of the lever 20 to the position shown in Fig. 1 exerts tension upon the spring 22 25 which remains in such position until the bolt 18 is withdrawn when the said spring 22 returns the switch blades 25 to engagement between the contacts 29 and 30, and complete the circuit.

30 When used with a door lock of ordinary construction provided with an integral locking bolt it is designed that the door be locked by use of such bolt only from the outside, and that any auxiliary locking means, as a separate bolt or other approved means be provided for locking the door from the inside. When used in connection with the lock mentioned as forming the subject-matter of a pending application, the same lock may be 35 employed for locking the door from the outside and the inside and when locked from the inside, the lights are not extinguished, but

when locked from the outside they are extinguished.

What I claim is:—

1. In an electric switch, a frame, spaced contacts mounted within the frame, a switch pivoted upon the frame and adapted to engage the contacts, a switch operating lever journaled upon the frame, and extending 45 downwardly without the frame, and a resilient member within the frame adapted to automatically close the switch when the lever is released.

2. In an electric switch, a frame adapted 50 for association with a door lock and provided with an opening adapted to receive a bolt of the lock, contacts mounted upon the frame, a switch pivoted upon the frame and arranged to make connection between the contacts, a switch operating lever journaled upon the frame and provided with a notch and having an arm extending over a portion 55 of the bolt receiving opening, a pin rigidly engaging the switch and positioned within the notch of the operating lever, and a spring connected with the operating lever and the pin, and whereby the operating lever is capable of a limited movement independent of the switch and to throw the switch suddenly 60 under tension of the spring.

3. The combination with a strike plate having a bolt opening, of a lever fulcrumed intermediate its ends, and with one end extending across the bolt opening and the 65 other connected with a retracting spring, and a switch blade actuated by the lever.

In testimony whereof I affix my signature in presence of two witnesses.

WILLIAM E. HUGHES.
